DESIGN FOR A SLICING MACHINE

Harry Weiner, Spring Valley, N. Y.

Application November 9, 1940, Serial No. 96,444

Term of patent 7 years

To all whom it may concern:

Be it known that I, Harry Weiner, a citizen of the United States and a resident of the city of Spring Valley, in the county of Rockland and State of New York, have invented a new, original, and ornamental Design for a Slicing Machine, of which the following is a specification, reference being had to the accompanying drawings which form part thereof, wherein

Fig. 1 is a rear perspective view of a slicing machine showing my new design; and Fig. 2 is a front perspective view thereof.

I claim:

The ornamental design for a slicing machine, as shown.

HARRY WEINER.
